FLASHLIGHT

Harvey Hill Turner, Woodbury, Ga., and Joseph
Calvin La Mar, Hawesville, Ky.

Application June 23, 1945, Serial No. 601,178

6 Claims. (Cl. 240—10.6)

1

This invention relates to new and useful improvements in a flashlight.

More particularly the invention proposes a new and improved flashlight which is characterized by the fact that it includes a casing for the battery cells, and which is also provided with a transverse tubular top portion having a passage or opening, and a tubular or annular lamp, so that it is possible to look through the tubular top portion while inspecting objects upon which the flashlight is aimed.

Still further the invention proposes providing the transverse tubular top portion with a sighting tube to facilitate looking through the flashlight as stated above.

The invention also makes use of a removable lens mounted upon the back of the sighting tube to obtain a clearer view of an object being inspected.

Still further the invention proposes to construct the tubular casing of the flashlight of several sections which will permit the tubular, or annular lamp to be easily removed and replaced when needed.

Still further it is proposed to present a modified form in which an improved sighting tube is used, constructed of telescopic sections which may be extended and retracted for controlling the cone of vision through the sighting tube.

Another object of this invention is the construction of the flashlight as briefly explained which is simple, durable, efficient and which may be manufactured and sold at a low cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a front elevational view of a flashlight constructed in accordance with this invention.

Fig. 2 is a side elevational view of the flashlight shown in Fig. 1.

Fig. 3 is a fragmentary enlarged vertical sectional view taken on the line 3—3 of Fig. 1.

Fig. 4 is a fragmentary transverse elevational view looking in the direction of the line 4—4 of Fig. 3.

Fig. 5 is a fragmentary enlarged elevational view looking in the direction of the line 5—5 of Fig. 3.

2

Fig. 6 is a fragmentary sectional view of another flashlight, this view being very similar to Fig. 3, but disclosing a modified form of the invention.

Fig. 7 is a fragmentary transverse sectional view taken on the line 7—7 of Fig. 6.

Fig. 8 is a fragmentary transverse sectional view taken on the line 8—8 of Fig. 6.

The new and improved flashlight, in accordance with that form of the invention illustrated in Figs. 1 to 5 inclusive, includes a tubular casing 10 for the battery cells 11. This tubular casing 10 has a transverse tubular top portion 12 which is removably mounted by a threaded section 13 upon a top portion 14 of the casing 10. The transverse tubular top portion 12 is provided with a front section 15 which is attached to it by several rivets, or fastening elements 16. This front section 15 is provided with a tubular threaded portion 17 forming a socket for a tubular, or annular electric lamp 18. A suitable reflector 18a is provided behind the electric lamp 18. The front section 15 is also provided with a removable cap 19 which releasably holds a lens 20 which is mounted in position in front of the lamp 18. This lens 20 is shown provided with a central opening 21. However, this opening is not essential.

The electric lamp 18 has an annular glass envelope 24 in which there is an annular filament 25. This filament 25 has ends 26 and 27. One of these ends is connected with the threaded shell 28 of the lamp 18, which is adapted to threadedly engage the threaded socket 17. The other end 35 of the filament 25 is connected with an annular contact 30 mounted upon the back of the lamp 18.

An electric circuit is established between the battery cells 11 and the electric lamp 18. This electric circuit is not shown in detail, but includes the usual switch 32 mounted upon the side of the tubular casing 10. The electric circuit also includes a contact arm 33 which engages against the annular or ring contact 30, and which is connected with a terminal 34 engaging the end terminal 35 of the uppermost battery cell 11. The terminal 34 is supported on a bar 36 mounted on and across the top portion 12 of the casing 10. The shell contact 28 of the electric lamp 18 is grounded because it is in contact with the socket 17 which is indirectly connected with the casing 10 of the flashlight.

The sighting tube 38 is mounted on and through the back of the tubular top portion 12 and is aligned with the central opening of the annular

lamp 18. This sighting tube 38 has a threaded portion 39 which threadedly engages a socket portion 40 formed upon the back of the top portion 12. A lens 42 is removably mounted across the back of the sighting tube 38. This lens 42 is releasably held in position by an annular member 43 which threadedly engages the end of the sighting tube 38.

The operation of the new and improved flashlight may be understood from the following:

The switch 32 is operated in the usual way to turn on, or turn off the lamp 18. The light rays will pass through the lens 20 and may be played upon an object. The object may be viewed better by looking through the sighting tube 38 because then the light rays from the lamp 18 are shielded from the viewer's eyes. Moreover, the viewer is looking upon the object from a shielded, or darkened area which makes viewing easier.

When required, the lamp 18 may easily be removed and replaced. The lens 42 may be removed and replaced.

In Figs. 6 to 8 inclusive, a modified form of the invention has been disclosed which is similar to the prior form distinguishing merely in the fact that the new and improved flashlight is provided with a sighting tube 48 formed from telescopic sections 49 and 50. The section 49 has a threaded back portion 39 which threadedly engages the socket 40. The front section 50 has a tapered front end. This front section 50 extends through the annular lamp 18 and into the opening 21 of the lens 20. A flexible handle 52 is attached upon the extendable section 50 by which it may be pulled out. A pin 53 is mounted upon the inner section 50 and engages an elongated slot 54 formed in the outer section 49 by which the sections are held against coming apart when the outer section 50 is pulled outwards.

In other respects this form of the invention is identical to the prior form and similar parts may be recognized by the same reference numerals.

The operation of this form of the invention is similar to the prior form distinguishing merely in the fact that the telescopic section 50 may be extended when desired so as to contract the cone of vision through the sighting tube 48. With this arrangement it is possible to better inspect small openings and objects.

This is merely one example of the adaptability of the present construction. It is to be understood that it may as readily be combined with other means suitable for medical purposes, such as those used for examining ears, throat, etc., where a concentrated area of light is desired.

For example, the inner section 50 may be in the form of a split conical tubing for ready insertion into the ear or other orifice. This split conical tubing may then be extended by any suitable arrangement such as a lever, slide arm, etc.

While we have illustrated and described the preferred embodiments of our invention, it is to be understood that we do not limit ourselves to the precise constructions herein disclosed and the right is reserved to all changes and modifications coming within the scope of the invention as defined in the appended claims.

Having thus described our invention, what we claim as new, and desire to secure by United States Letters Patent is:

1. In a flashlight having a tubular top portion formed with spaced end walls and a lamp socket mounted concentrically in one end wall,

a tubular electric lamp mounted in said lamp socket, a sighting tube mounted through the other end wall of the tubular top portion concentric with said tubular electric lamp, and a lens mounted on the end wall of the tubular top portion formed with the lamp socket for concentrating rays of light from said lamp on an object in front of said lens, said lens being formed with an opening concentric with said tubular electric lamp and said sighting tube providing an unobstructed clear line of vision between an object in front of said lens and one's eye behind said sighting tube.

2. In a flashlight having a tubular top portion formed with spaced end walls and a lamp socket mounted concentrically in one end wall, a tubular electric lamp mounted in said lamp socket, a sighting tube mounted through the other end wall of the tubular top portion concentric with said tubular electric lamp, and a lens mounted on the end wall of the tubular top portion formed with the lamp socket for concentrating rays of light from said lamp on an object in front of said lens, said lens being formed with an opening concentric with said tubular electric lamp and said sighting tube providing an unobstructed clear line of vision between an object in front of said lens and one's eye behind said sighting tube, a second lens mounted within an enlarged recess formed in one end of said sighting tube, and an annular member threadedly engaged in said enlarged recess and bearing against said second lens securing the same in position.

3. In a flashlight having a tubular top portion formed with spaced end walls and a lamp socket mounted concentrically in one end wall, a tubular electric lamp mounted in said lamp socket, a sighting tube mounted through the other end wall of the tubular top portion concentric with said tubular electric lamp, and a lens mounted on the end wall of the tubular top portion formed with the lamp socket for concentrating rays of light from said lamp on an object in front of said lens, said lens being formed with an opening concentric with said tubular electric lamp and said sighting tube providing an unobstructed clear line of vision between an object in front of said lens and one's eye behind said sighting tube, said sighting tube being formed of telescopically engaged sections with one section projected from the other and through said tubular lamp, means non-rotatively but axially extendably connecting said sections together, and means attached to the projected section and extended through the opening in said lens by which said section can be extended and retracted relative to each other.

4. In a flashlight having a tubular top portion formed with spaced end walls and a lamp socket mounted concentrically in one end wall, a tubular electric lamp mounted in said lamp socket, a sighting tube mounted through the other end wall of the tubular top portion concentric with said tubular electric lamp, and a lens mounted on the end wall of the tubular top portion formed with the lamp socket for concentrating rays of light from said lamp on an object in front of said lens, said lens being formed with an opening concentric with said tubular electric lamp and said sighting tube providing an unobstructed clear line of vision between an object in front of said lens and one's eye behind said sighting tube, said sighting tube being formed of telescopically engaged sections with one section projected from the other and through said tubular lamp, means

non-rotatively but axially extendably connecting said sections together, and means attached to the projected section and extended through the opening in said lens by which said section can be extended and retracted relative to each other, said projected section having its projected end tapered.

5. In a flashlight having a tubular top portion formed with spaced end walls and a lamp socket mounted concentrically in one end wall, a tubular electric lamp mounted in said lamp socket, a sighting tube mounted through the other end wall of the tubular top portion concentric with said tubular electric lamp, and a lens mounted on the end wall of the tubular top portion formed with the lamp socket for concentrating rays of light from said lamp on an object in front of said lens, said lens being formed with an opening concentric with said tubular electric lamp and said sighting tube providing an unobstructed clear line of vision between an object in front of said lens and one's eye behind said sighting tube, said sighting tube being formed of telescopically engaged sections with one section projected from the other and through said tubular lamp, means non-rotatively but axially extendably connecting said sections together, and means attached to the projected section and extended through the opening in said lens by which said section can be extended and retracted relative to each other, said latter-mentioned means comprises a handle attached at one end to said projected section and having its other end extended through said lens opening to be manually grasped for sliding said projected section relative to the other section.

6. In a flashlight having a tubular top portion formed with spaced end walls and a lamp socket mounted concentrically in one end wall, a tubular electric lamp mounted in said lamp socket, a sighting tube mounted through the other end wall of the tubular top portion concentric with said tubular electric lamp, and a lens mounted on the end wall of the tubular top portion formed

with the lamp socket for concentrating rays of light from said lamp on an object in front of said lens, said lens being formed with an opening concentric with said tubular electric lamp and said sighting tube providing an unobstructed clear line of vision between an object in front of said lens and one's eye behind said sighting tube, said sighting tube being formed of telescopically engaged sections with one section projected from the other and through said tubular lamp, means non-rotatively but axially extendably connecting said sections together, and means attached to the projected section and extended through the opening in said lens by which said section can be extended and retracted relative to each other, said latter-mentioned means comprises a handle attached at one end to said projected section and having its other end extended through said lens opening to be manually grasped for sliding said projected section relative to the other section.
